INVENTOR.

Elsa Deutsch
BY Robert Irving Williams

ATTORNEY

UNITED STATES PATENT OFFICE

152,522

DESIGN FOR A BROOCH OR SIMILAR ARTICLE

Elsa Deutsch, Bat Cave, N. C.

Application September 19, 1947, Serial No. 141,490

Term of patent 3½ years

(Cl. D45—19)

To all whom it may concern:

Be it known that I, Elsa Deutsch, a citizen of the United States, and a resident of Bat Cave, county of Henderson, State of North Carolina, have invented a new, original, and ornamental Design for Brooch or Similar Article, of which the following is a specification, reference being had to the accompanying drawing, forming part thereof.

In the drawing:

Fig. 2 is a side view thereof.

I claim:

The ornamental design for a brooch or similar article, as shown.
